OF D 17,644

DESIGN.

—
O. HEINIGKE.

CARPET.

No. 17,644.

Patented Aug. 23, 1887.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 17,644, dated August 23, 1887.

Application filed July 21, 1887. Serial No. 244,944. Term of patent 3½ years.

To all whom it may concern:

Be it known that I, OTTO HEINIGKE, of New Utrecht, Long Island, New York, have invented a new and original Design for Carpets, 5 of which the following is a specification; reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

15 The characteristic features of my design are the composite figure or group A and the tracery ground-work upon which the group A is repeated over the face of the carpet. The figure A has three fan-shaped leaves, forming 20 a triangular group at the central and lower part of the figure. Around the upper and larger fan-shaped leaf is a body of geometrical

work, consisting of double-diamond-shaped figures, most of which have a square ornamental form at the center of the upper diamond. The sides of the figure A are formed by small and irregular ornamental figures, somewhat coral-like in character. This figure A is repeated at regular intervals over the face of the design, and the interspaces are filled 25 with a running tracery ground which frames the spaces occupied by the figure A.

What I claim as new, and desire to secure by Letters Patent, is--

1. The design for carpets, consisting of the 35 figure A, substantially as shown.
2. The design for carpets, consisting of the figures A and the tracery ground, substantially as shown.

OTTO HEINIGKE.
